UNITED STATES PATENT OFFICE.

JULES P. GITS, OF CHICAGO, ILLINOIS.

OIL-CUP.

1,350,721.

Specification of Letters Patent. Patented Aug. 24, 1920.

Application filed December 15, 1919. Serial No. 345,024.

To all whom it may concern:

Be it known that I, JULES P. GITS, a citizen of the United States, residing at Chicago, in the county of Cook and State of Illinois, have invented a certain new and useful Improvement in Oil-Cups, of which the following is a specification.

This invention relates to oil cups for all sorts of machines and particularly to closures for the same. The object of the invention is to provide an oil cup, with a spring actuated cover, hinged thereto with a minimum number of parts, thus reducing to smallest possible amount the punch or die work to be done and the consequent expense of the device. The invention consists in means for carrying out the foregoing objects, which can be easily and cheaply made, which is efficient and satisfactory in operation and is not readily liable to get out of order. More particularly the invention consists in the details of construction hereafter more fully set forth in the specification and claims.

25 Referring to the drawings in which like numerals represent the same parts,

Figure 1 is a side, and

Fig. 2 an end view of the mechanism illustrating this invention in its preferred form.

30 Fig. 3 is a central sectional detail view taken in the same position as Fig. 1 on the line 3 of Fig. 2.

Fig. 4 is a perspective view of the four parts constituting the device of this invention, separated one from the other.

In carrying out this invention, a body member 10 is drawn or punched from sheet metal with an open top end 12 and a contracted bottom discharge nozzle 14 of the usual form. In the operation of forming this body 10, an elongated metallic hinge inclosing strip 16 is provided, originally extending straight up upon the side wall of the cup but ultimately bent down in the curved form shown to substantially inclose the spring 18 and the pivot pin 20, as shown. The cover 22 is stamped out of one piece of metal so as to form a flange 24 extending down and around the upper edge of the cup 10 as clearly shown in the drawing, except at the portion where the member 16 is located. At this latter point, the cover 22 is elongated into the projecting surface 26 from which depends the ears 28 carrying perforations 30 entered by the pivot pin 20.

One end 32 of the spring 18 hooks over the edge of cover portion 26 while the other end 34 of this spring lies between the end of member 16 and the body of cup 10 as clearly appears in Fig. 3, the result being that whenever the cover 22 is rotated in a clockwise direction, as shown in Figs. 1, 2, and 3, the spring is worked against or set so that when the cover is released, the spring throws the cover back to closed position. The 60 spring 18 is always loose enough on pivot 20 to permit this action. The side of member 16, where spring end 32 goes up to engage the cover portion 26, is notched at 37 so as to provide an opening 39 (Fig. 2) in which 70 the spring lies and moves. The portion of member 16 above notch 37, i. e., between it and the body of cup 10, is the full width of portion 26 of cover 22 between ears 28 so that when the heads of pin 20 are riveted 75 up, they cannot force the ears into interference with the spring.

In the particular case here illustrated, the member 10 is notched vertically in the lines 38 on opposite sides of inclosing strip 16 so as to more readily insure the cover 22 fitting closely on the upper edge of cup 10, but this detail of construction is not a limitation upon this invention. These notches provide small air intakes 40 shown in Fig. 3 which 85 permit the entrance of sufficient air so that oil can flow down opening 14 while cover 22 is closed.

From the foregoing, it will be seen that all the manufacturer has to do is to provide the 90 four simple parts shown in Fig. 4, thread the pin or rod 20 through the spring 18 and through the holes 30, then place the inclosing strip 16 of the cup 10 around the spring and below the member 26 and bend it to 95 place, as shown, whereupon the cup of this invention is ready for use in the obvious manner.

Having thus described my invention what I claim as new and desire to secure by Letters Patent, is:

1. In mechanism of the class described, an oil cup chamber, a cover therefor, a pivot pin having its opposite ends bearing in the cover, a spring about said pivot having one 105 end bearing on the cup, an enveloping strip formed on the side of the cup member, embracing said spring member and pivot to, without unitary connection therewith, so hold the second end of the spring that, when 110

the cover is moved off the cup the spring tends to close the cover, for the purposes set forth.

2. An oil cup including a body having a projecting integral hinge inclosing strip of metal initially extending from one side thereof, then laterally bent first outwardly then downwardly to form a retaining device on the side of the cup for the pivot mechanism of the hinge, a cover over the top of the cup, having ears extending to the sides of said strip, a spring with a pivot pin inclosed therein mounted inside the strip member with the ends of said pivot pin in engagement with said lugs on the cover, while the ends of the spring are detachably locked one to an ear on the cover, the other between the end of the inclosing strip and the body of the cup, so that it will force the cover closed, for the purposes set forth.
3. In mechanism of the class described, an

oil cup chamber, a cover therefor, a pivot pin having its opposite ends bearing in the cover, a spring about said pivot having one end bearing on the cup and an enveloping strip formed on the side of the cup member passing up the side of the cup, over the spring, and thence down around the outside of the spring embracing said spring member and pivot so as to form the only support on the cover for the pivot member and to hold the second end of the spring so that when the cover is moved off the cup, the spring tends to close the cover, for the purposes set forth.

In witness whereof I have hereunto subscribed my name in the presence of two witnesses.

JULES P. GITS.
